United States Patent [19]

Gamm

[11] Patent Number: Des. 280,949

[45] Date of Patent:  Oct. 15, 1985

[54] ATHLETIC SHOE WITH PADDED COUNTER

[75] Inventor: Robert J. Gamm, St. Louis County, Mo.

[73] Assignee: Kangaroos U.S.A. Inc., St. Louis, Mo.

[] Term: 14 Years

[21] Appl. No.: 481,167

[22] Filed: Apr. 1, 1983

[52] U.S. Cl. D2/310; D2/314

[58] Field of Search ..... D2/309, 310, 311-313, D2/320, ; 36/32 R, 83-84, 69-71, 72 R, 72 A, 73, 113-115, 105, 128, 129, 136
